UNITED STATES PATENT OFFICE.

BURTON D. MYERS, OF WALLINGFORD, CONNECTICUT, ASSIGNOR TO THE SIMEON L. AND GEORGE H. ROGERS CO., OF WALLINGFORD, CONNECTICUT, A CORPORATION.

DESIGN FOR A SPOON, FORK, OR SIMILAR ARTICLE.

46,368.

Specification for Design.

Patented Sept. 8, 1914.

Application filed July 13, 1914. Serial No. 850,836. Term of patent 7 years.

To all whom it may concern:

Be it known that I, BURTON D. MYERS, of Wallingford, in the county of New Haven and State of Connecticut, have invented a new, original, and ornamental Design for a Spoon, Fork, or Similar Article, of which the following is a specification, reference being had to the accompanying drawing, forming part thereof.

Figure 1 is a face view of a spoon, fork

or similar article, showing my new design. Fig. 2 is a detail perspective view.

I claim:

The ornamental design for a spoon, fork or similar article, as shown.

BURTON D. MYERS.

Witnesses:

JOHN A. MARTIN,
A. I. MARTIN.
